UNITED STATES PATENT OFFICE

ARNT WILHELM WEESMAN, OF CHICAGO, ILLINOIS, ASSIGNOR TO INTERNATIONAL HARVESTER COMPANY, A CORPORATION OF NEW JERSEY

GRAIN WEIGHER

Application filed April 6, 1928. Serial No. 267,825.

The invention relates to grain weighers designed for use in connection with threshing machinery.

Particularly, the invention has to do with an automatic grain weigher wherein a double hopper or receiver receives predetermined, uniform charges of grain, or the like, the weight of the charge causing the receiver to move downwardly and also to swing or oscillate. The down movement, being against a counter-balance, determines the weight of the charge, and the oscillatory movement insures an alternate supply to the compartments comprising the double hopper. These compartments are provided with doors alternately controlled to open for discharging the weighed charges or loads of grain.

The object of the invention is to provide an improved grain weigher structure of the type mentioned.

Generally, the invention consists in certain features of construction and combination of parts as hereinafter described and claimed. In order that these features may be fully understood, reference is made to the accompanying sheets of drawings, wherein:

Figure 1 is a general side elevational view of the improved weigher in combination with a thresher, elevator, and discharging mechanism;

Figure 2 is a similar view with the compartmented hopper appearing in section;

Figure 3 is a front, or end view elevation; and

Figure 4 is a top plan view.

In these drawings, a threshing machine is shown at 10 having an upright elevator 11 provided with a stationary discharge spout 12. Obviously, the invention about to be disclosed is equally applicable for use with elevators of different kinds, and the form depicted in the drawings is, therefore, merely by way of example.

Adjacent its upper end, the elevator carries on each side, a plate 13 provided with pivot pins 14 for pivotally carrying a rectangularly shaped scale beam 15, said beam being bifurcated at one end to form arms 16 embracing the discharge end of the spout 12, as shown. The opposite end of the beam car-

ries a fixed weight 17 and along one side a slidable or adjustable weight 18.

One side of the discharge end of the spout 12 carries a plate 18' having a rounded under side 19 and flattened ends 20. The purpose of this plate will later appear. The hopper structure and the manner of its mounting will next be described.

The free ends of the arms 16 each carry a pivot pin 21 to which are connected a pair of triangularly-shaped hangers 22, there being one such hanger on each side, as shown. The lower ends of these hangers terminate in spaced legs or arms 23. The arms 23 on the hangers nearest the elevator 11 are pivotally connected to a forked arm 24 in turn pivotally connected to said elevator. These hangers 22 carry a shaft 25 on which is mounted adjacent each hanger a bracket 26, each bracket being provided with two, diverging, upstanding arms 27. These bifurcated brackets 26 are secured to the end walls 28 of a polygonally-shaped weigher hopper 29. In this manner the hopper is carried by the scale beam 15 underneath the discharge spout 12.

This hopper, which constitutes the weighing or measuring receiver, is provided with a central partition wall 30 running lengthwise to divide said hopper into two substantially equal compartments A and B. When this hopper is empty, it is in equilibrium on the scale beam with the counter-weights and, as a result, the partition wall 30 is substantially vertically disposed under substantially the exact center of the delivery spout 12 discharge end. The compartment A is provided with a grain receiving port 31 at its top, and, at its bottom, it is provided with a discharge port 32. Similarly, the compartment B has a receiving port 33 and a discharge port 34. Each of these discharge ports is adapted to be closed by a door, said doors, however, it is to be noted, not being carried by the hopper, as will now appear. Each leg 23 of the hangers 22 has doors pivotally connected thereto, the door 35 being for the port 32, and the door 36 being for the port 34. The door 35 is additionally pivotally connected to a link 37 which in turn is pivotally connected to the upper, free end 100

of one of the arms 27, while the other door 36 is similarly supported by a link 38 from the other arm 27, as shown.

Underneath the weighing hopper, the 5 thresher carries an unloading conveyer 39 provided with a hopper-like receiving funnel 40. This structure receives and carries away the weighed quantities of grain.

The back end of the hopper carries an upper right arm 41 provided with a free running 10 roller 42 adapted to engage the ends 20 of the plate 18, or to roll under the rounded edge 19 of said plate for a purpose presently to appear.

15 In operation we may assume that the weighing and measuring hopper has been tilted to the position shown in Figure 2 with the port 33 of the compartment B in position to receive a charge of grain from the spout 12. The hopper will be held in this position 20 by engagement of the roller 42 with a flat end 20 of the plate 18, as shown. In this position, the oscillation of the hopper to the position now being considered has caused the link 38 to hold the door 36 closed. Grain is flowing 25 into the compartment B, and, when a predetermined weight or amount thereof has accumulated in said compartment, the scale beam 15 is overbalanced, causing the entire 30 hopper to descend, which disengages the roller 42 from the left hand end 20 of the plate 18. With the hopper thus unlatched, the preponderant weight on one side causes the hopper to oscillate, as will be clear. The 35 roller then rides under the plate 18 and the hopper tilts to swing the receiving port of compartment B away from the spout 12. At the same time, the door 36 is opened to permit the contents of compartment B to discharge 40 into the funnel 40. In the meantime, compartment A has tilted to receiving position with its door 35 closed. The outflow from compartment B quickly relieves the overbalance of the scale beam, causing the hopper to 45 ascend with the roller 42 now locking over the other flat end wall 20 of the plate to hold compartment A in receiving position. Thus, the operation will progress, one compartment being filled until the scale beam is overbalanced, then the hopper automatically oscillating itself to cause the filled compartment 50 to be discharged and the unfilled compartment to be charged until it, in turn, is filled, then another oscillation with similar results, 55 and so on. If desired, any approved form of counting device may be associated with this mechanism to register the number of measured units of grain which have passed 60 through the weighing hopper.

It is the intention to cover all such changes and modifications of the form herein disclosed as do not materially depart from the spirit and scope of the invention as hereinafter claimed.

What is claimed is:

1. In a weigher, the combination of a scale beam fulcrumed on a support, hangers carried by said beam, a shaft carried by the hangers, a hopper, brackets carried by the 70 hopper and rockably mounted on the shaft, a plate on the support, said plate having a rounded bottom and a flat end, and a roller carrying arm secured to the hopper for co-operating with said plate to hold the hopper 75 against rocking movement.

2. The combination with an elevator having a fixed spout, of a scale beam fulcrumed on the spout, hangers depending from the beam and pivotally connected to the elevator, 80 a rockable hopper carried by the hangers, a latch plate on the spout including a flat end and round bottom, and a roller carrying arm on the hopper cooperable with the plate to prevent rocking movement of said hopper. 85

3. The combination with an elevator having a fixed spout, of a scale beam fulcrumed on the elevator and carrying a pair of hangers which in turn are pivotally connected to said elevator, a double compartment hopper rockably carried by the hangers, said hopper compartments having charging ports underneath the spout and discharging ports at their bottoms, brackets on the hopper, doors for the discharge ports pivotally carried by the 95 hangers, links pivotally connecting the doors to the brackets, a latch plate on the spout, said plate having flat ends and a rounded bottom, an upstanding arm carried by the hopper, and a roller on the arm, said roller 100 adapted to cooperate with the latch plate to hold one of the compartments in a position to communicate with the elevator spout.

In testimony whereof I affix my signature.
